FIG. 1 is a top, right side, and front perspective view of a shopping cart support assembly of the present disclosure;

FIG. 2 is a right side elevational view thereof;

FIG. 3 is a left side elevational view thereof;

FIG. 4 is a top elevational view thereof;

FIG. 5 is a bottom elevational view thereof;

FIG. 6 is a front elevational view thereof with the rear elevational view being an identical mirror image that is omitted; and,

FIG. 7 is an enlarged left side, perspective view of an interior region thereof.

The broken lines in the drawings are for illustrative purposes and form no part of the claimed design.
